UNITED STATES PATENT OFFICE

135,035

DESIGN FOR A ROOFING SHINGLE

Don B. Humphrey, Great Neck, N. Y., assignor to United States Gypsum Company, Chicago, Ill., a corporation of Illinois

Application June 12, 1942, Serial No. 107,180

Term of patent 14 years

To all whom it may concern:

Be it known that I, Don B. Humphrey, a citizen of the United States, residing at Great Neck, in the county of Nassau and State of New York, have invented a new, original, and ornamental Design for a Roofing Shingle, of which the following is a specification, reference being had to the accompanying drawing, forming a part thereof,

The figure is a plan view of a roofing shingle embodying the design.

I claim:

The ornamental design for a roofing shingle, substantially as shown.

DON B. HUMPHREY.
